UNITED STATES PATENT OFFICE.

TALBOT C. DEXTER, OF PEARL RIVER, NEW YORK.

PAPER-FEEDING MACHINE.

SPECIFICATION forming part of Letters Patent No. 605,088, dated June 7, 1898.

Application filed April 17, 1897. Serial No. 632,629. (No model.)

To all whom it may concern:

Be it known that I, TALBOT C. DEXTER, a citizen of the United States, residing at Pearl River, county of Rockland, State of New York, have invented certain new and useful Improvements in Automatic Throw-Out and Stop Mechanism for Paper-Feeding Machines, of which the following is a specification.

In Patent No. 567,302, granted to me September 8, 1896, for automatic stop-motion device, and application for patent filed by me December 28, 1896, Serial No. 617,263, for improvements in paper-feeding machines, I have described and claimed, among other devices, certain improvements in mechanisms for automatically arresting the operation of the machine in case two or more sheets are simultaneously fed forward by the feeding instruments, said mechanisms comprising in both of the above-named cases an automatic clutch adapted to disengage the machine from the power-shaft and positively arrest its movement and an electric sheet-caliper device actuated by the thickness of two or more sheets of paper and suitably connected with the automatic clutch for actuating it and causing it to throw the machine out of operation.

My present invention relates to improvements in the automatic throw-out and stop mechanisms above referred to; and it consists mainly of novel features in the sheet-caliper device for actuating the automatic clutch, and incidentally to a novel arrangement or combination of devices for improving the operation of the automatic clutch to render it quick and sure.

In order that my invention may be fully understood, I will first describe the same in connection with the accompanying drawings and afterward point out the novelty with more particularity in the annexed claims.

In said drawings, Figure 1 is a detail plan view of one corner of a paper-feeding machine embodying my improvements. Fig. 2 is a detail front perspective view of the main driving-gear and attached automatic clutch and stop mechanism. Fig. 3 is a detail sectional side elevation of the clutch-operating mechanism and the controlling electric trip. Fig. 4 is a detail perspective view of the adjustable automatic caliper device which controls the electric trip of the clutch-operating

mechanism. Fig. 5 is a similar view of a slightly-modified form of the same device.

I have represented my improvements as applied to the paper-feeding machine covered by my above-named application, Serial No. 617,263, and have indicated the parts of said machine which remain unchanged by the same reference-numbers used in the other case. I refer to said application for a fuller understanding of the machine, though I herein give a sufficient description to enable those skilled in the art to comprehend my present invention.

1, 2, 3, and 452 indicate parts of the feeder-frame.

115 represents the main power-shaft of the machine, said shaft extending transversely across the machine above the delivery end and operating all the feeding mechanisms through suitable connections.

If more than one sheet of paper passes from the feeding-machine, it is necessary to arrest the movements of the several mechanisms till the error can be corrected. In the path of the sheets a sheet-caliper device is arranged and suitably connected to the clutch-operating mechanism to throw the clutch when more than the proper number of sheets pass. I will proceed to describe this mechanism, first referring to the automatic clutch and then to the automatic sheet-caliper device which controls the same.

Loosely journaled upon the outer end of the main driving-shaft 115 is a large power-gear 320, which has secured to it or formed integral with it a clutch-disk 321, having a radial notch 322. Keyed to the outer end of the shaft 115, adjacent to the clutch-disk 321, is a similar disk 323, secured by means of a key 324 and formed with a radial notch 325. Pivoted upon a pin 326, supported in the lug 326^a, projecting from and formed integral with the aforesaid clutch-disk 323, is a clutch-dog 327, having an engaging tooth 328, which is adapted to engage in the radial notches 322 and 325 of the clutch-disks when said notches register or correspond in position.

329 is a pin projecting from one side of the dog 327, and 330 is a rod pivoted to pin 329 and projecting through a guide-lug 331, projecting from the disk 323.

332 is a spiral spring confined upon the rod

330 between the lug 331 and collar 333 for holding the dog 327 against the peripheries of the clutch-disks and forcing the tooth 328 into the notches 322 325 when they assume proper 5 position.

334 is a head or enlarged lug formed integral with the clutch-disk 323.

336 is a heel portion formed integral with the clutch-dog 327, said heel portion projecting over the enlarged lug or head 334 into the plane of the disk 323 in position to be engaged by head 339, hereinafter referred to, which head can be moved into the path of heel 336 (for disengaging the clutch-dog 327) and head 15 334 to arrest the motion of the machine.

337 is a bracket secured to the side frame-bar 1, and 338 is a pin supported upon said bracket.

339 is a sliding head having two arms 339^a 20 and 339^b projecting from it and sliding upon pin 338 and provided with a guide-strap 340 on the arm 339^a, which embraces a guide-pin 341, projecting from the main frame.

342 is a rock-shaft journaled in bearings 25 343 of the main frame, and 344 is a rock-arm secured to one end of the shaft 342 by means of set-screw 345. The lower end of the rock-arm 344 is forked or bifurcated at 346 to engage the arm 339^b of the sliding head 339.

397 is one of a pair of rock-arms, and 400 30 is a shaft journaled in bearing 399 and carrying drop-rollers 402.

404 are rock-arms suitably connected with rock-arms 397 and carrying an antifriction-roll 405 at their upper ends, which operates upon the periphery of a cam 406, which is keyed to the shaft 115 inside of the bearing 115^a of the main frame.

417 is a transverse rock-shaft having hand-levers 417^a and geared to the rock-shaft 342 by means of bevel-gears 419 and 420. Keyed to the rock-shaft 417 is a rock-arm 416, from which extends a rod 415, which is connected in any suitable manner to a device for holding the drop-rollers in elevated inoperative 45 position when the machine is not running.

The mechanism so far described is fully illustrated and explained in my application, Serial No. 617,263, above referred to, and will 50 be more fully understood by carefully examining said application.

Projecting up from the shaft 417 is a rock-arm 25, which is pivoted at 26 to the down-turned end 27^a of the bar 27, which is movably supported at its opposite end by means of a slot 27^b, cut in the bar and working upon or engaging a pin 28 in the upper end of the plate or casting 29, which is secured to the frame-piece 3. Pivoted upon a pin 35 is a dog 60 or detent 36, having a heel 36^a, from which extends a spiral spring 37 to an eyebolt 38, secured in the flange or indent portion 39 of the bar 27. Journaled upon a pin 40 is a dog 41, having a hook end 41^a, adapted to engage

65 the heel 36^a of the dog 36. The dog 41 carries an armature 42, which rests adjacent to the electromagnet 43, which is mounted upon

a bracket 44, adjustably secured to the bar 27. The spiral spring 45 tends to hold the armature 42 away from the magnet and the hook 41^a into engagement with heel 36^a for keeping the dog or detent 36 out of engagement with the clutch-operating bar, which I will now describe.

Keyed to the main power-shaft 115 is an oval-shaped cam 60, and supported loosely upon the shaft to one side of said cam is a guide-loop 61, formed integral with a constantly-reciprocating bar 62, which extends forwardly and reciprocates freely in the guide-frame 63. Journaled upon a pin 64 at one end of guide-loop 61 is an antifriction-roller 65, which operates upon the periphery of cam 60, the bar 62 being held yielding toward the cam by a suitable spring. (Not shown.) Formed on the upper edge or face of the bar 62 is a notch or shoulder 70, having an inclined face 71, and to the rear of shoulder 70 is a cam-lug 72. The bar 62 operates directly beneath the dog or detent 36, and should the electromagnet be energized the dog 41 will release detent 36, which latter is forced into engagement with shoulder 70, which will cause the bar 27 to be moved forward for rocking shaft 417 and shifting the clutch of the machine. As the bar 62 is moved back after shifting the clutch the detent 36 will ride on cam 72 and throw heel 36^a into engagement with hook 41^a of dog 41, providing, of course, the magnet 43 has become deenergized by the return to normal position of the controlling sheet-caliper device.

I will now proceed to describe the automatic sheet-caliper device which throws into play the mechanism above described for shifting the clutch and arresting the movement of the machine when two or more sheets are fed simultaneously from the machine.

To properly caliper the passing sheets of paper and detect the presence of more than one sheet, it is essential that the device be free to move under the pressure of an unusual thickness of sheets and at the same time be capable of a very fine adjustment which will not be interfered with by the vibrations of the machine. To accomplish this, I propose to have the upper movable caliper member vertically adjustable upon an arm or frame which is rigidly connected with or is an integral part of the support for the lower stationary member, said movable member being capable of horizontal sliding movement under the action of the moving sheets for completing an electric circuit to a clutch-controlling device. The sheet caliper or detecting device is preferably located at the delivery end of the feeding-machine, so that the presence of more than one sheet passing from the feeder will be immediately detected and the machine stopped before the two or more sheets are fed into the folder or printing-press and destroyed.

Mounted upon the machine-frame piece

452 is a U-shaped frame or yoke 100, having a supporting arm or base 101 adjustably secured to the machine-frame in any suitable manner. (Not shown.)

5 102 is the lower stationary member of the caliper device, comprising a smooth bar or plate of metal having tapered or rounded ends 102^a. The surface of the plate 102 is flush with the plane of feed for the sheets.

10 105 is the short arm of the U-shaped yoke, and 106 is a vertically-extending bracket secured to arm 105 and having an elongated horizontal flange or plate 107, in which is formed a longitudinally-extending slot 108.

15 The upper movable member of the caliper device comprises a plate 110, having a lower smooth face, and a post 111, extending up from its upper face.

20 112 is an adjustable supporting-screw passing through the slot 108 of flange 107 and engaging a threaded opening in the upper end of post 111 for slidably supporting plate 110 in any adjusted position with relation to the plate 102. Upon the screw 112 is a clamp-

25 nut 113 for securing the screw in adjusted position. Projecting rearwardly from the plate 110 is an integral arm 115^a, which has a bifurcated end 116 supporting the journal-screws 117, which pivotally engage the lower

30 end 118 of the lever 119. The lever 119 is pivoted at 120 between integral lugs of an arm 121, extending from and forming an integral part of the short arm 105 of the U-shaped yoke 100. Extending from lever 119

35 below the pivot 120 is an arm 122, supporting a small adjustable weight 123. Attached to the upper end of lever 119 is a contact-spring 125, which may be brought into electric contact with an adjustable electric terminal 126,

40 supported in an insulated bearing 127 of a bracket-arm 128, forming continuation of arm 121. From the contact 126 the circuit-wire 129 extends to a battery 130, and from thence the wire 131 leads to the magnet 43. A short

45 wire 132 connects the other terminal of the magnet to the machine-frame, through which the circuit is completed to the contact-lever 119. The lever 119 is limited in its backward movement by a screw-stop 133, seated in a

50 threaded opening of the flange 134 of bracket-arm 128. An arm 135 extends forwardly from arm 105 and is provided with a journal-pin 136, upon which is freely journaled a curved guide-plate 137, which rests freely upon the 55 rear end of the plate 102, with its end adjacent to the caliper-plate 110.

It will be observed that the sheets of paper fed from the machine have their forward edges guided under the caliper-plate 110

60 by the curved guide-plate 137. The plate 110 is supported by screw 112 just far enough above the plate 102 to allow a single sheet to pass freely between them. If two sheets pass simultaneously under the caliper-plate, the

65 extra thickness will be accommodated by the plate 110 giving sufficiently in a vertical direction (the screw 112 having free play in the

slotted plate 107) to allow the two sheets to pass; but the friction caused by the thickness of the extra sheet will be sufficient to cause 70 the plate 110 to move with the paper a short distance, the screw 112 sliding in slot 108 to allow this movement. The movement of plate 110 with the paper rocks the lever 119 and makes contact between spring 125 and terminal 126, thereby energizing magnet 43, which attracts armature 42 and allows detent 36 to engage shoulder 70 and thereby operate the rock-shaft 417 for throwing the clutch out of gear and arresting the motion 80 of the machine.

The specific structure and operation of the clutch are immaterial to the present invention and are not more fully referred to.

In Fig. 5 I have shown the sheet-caliper device with a detecting wheel or roller in addition to the plate 110. The plate 110 in this form is provided with a lug or post 111^a, corresponding with post 111, and between posts 111 and 111^a is formed a slot 110^a. Journaled

upon suitable bearings 141 in post 111 and 90 111^a is the detecting-wheel 140, having its periphery projecting through the slot 110^a a little below the under surface of plate 110.

The roller 140 has a small block 142 of soft 95 rubber set in a segmental notch cut in its periphery and a pin 143 projecting from one face to limit its movement. The cut-out portion of the roller reduces its weight on that side of its center and causes it to rest normally with the upper block 142 and pin 143 above the center.

With the exception of the features noted this form of the caliper device is of the same construction as the form shown in Fig. 4. In operation the device is 105 adjusted to hold the lower periphery of the roll just above the surface of the passing sheets. Should two sheets pass simultaneously, the friction will be sufficient to rotate roller 140 to bring pin 143 into engagement 110 with post 111^a and the rubber block 142 into frictional engagement with the paper. The continued movement of the paper moves plate 110 forward and makes the electric contact

115 between spring 125 and terminal 126. The rubber block also has a retarding action upon the passing sheets.

It will be observed that the movement of the caliper-plate for making the electric contact is in a horizontal plane in the direction in which the sheets travel, whereas the caliper-plate is adjusted vertically with

120 relation to the stationary plate for detecting by the thickness the passage of more than one sheet and is at the same time free to move vertically to accommodate the extra thickness.

I am aware that it has been proposed to provide throw-out or stop mechanisms for paper-feeding machines with a rotative or pivoted sheet-gaging member supported adjacent to

125 the plane of movement of the sheets and capable of being moved on its pivot by the passing sheets for actuating the throw-out or stop mechanism. I am also aware that it has been

proposed to arrange the gaging member of such mechanisms to move perpendicularly to the plane of movement of the sheets when an extra thickness of sheets passes, and I therefore disclaim such structures in this application.

In my improved form of sheet gaging or caliper mechanism I arrange the sheet-caliper-clutch-controlling member to move bodily or slide in a plane parallel with the plane of feed of the sheets, and there is practically no limit to the length of stroke which can be imparted to this member and the connected parts, so that the mechanism can be rendered entirely independent of the vibrations of the feeding-machine.

Having thus described my invention, the following is what I claim as new therein and desire to secure by Letters Patent:

1. The combination, in a paper-feeding machine, with an automatic clutch mechanism constructed to throw the machine out of operation, of a sheet-caliper-clutch-controlling device comprising an electromagnetic trip mechanism, a lower stationary caliper member over which the sheets pass, an upper adjustably-supported sliding caliper member supported over the stationary member and capable of moving in a plane parallel with and in the direction of travel of the sheets and an electric contact device comprising a contact-point, and a contact-lever connected with the sliding caliper member, the contact point and lever being in circuit with the electromagnetic trip mechanism, substantially as set forth.

2. The combination, in a paper-feeding machine, with an automatic clutch mechanism constructed to throw the machine out of operation, of a sheet-caliper-clutch-controlling device comprising an electromagnetic trip mechanism, a lower stationary caliper member over which the sheets pass, an upper adjustably-supported caliper member supported over the stationary member and capable of moving in the direction of travel of the sheets, an arm extending from the movable caliper member, and an electric contact device in circuit with the electromagnetic trip mechanism and comprising a contact-lever extending transversely to the line of movement of the sheets and pivotally connected with the arm of the movable caliper member, and a contact-point with which the lever is brought into contact by the movement of the caliper member, substantially as set forth.

3. The combination, in a paper-feeding machine, with an automatic clutch mechanism constructed to throw the machine out of operation, of a sheet-caliper-clutch-controlling device comprising an electromagnetic trip mechanism, a lower stationary caliper member over which the sheets pass, an upper adjustably-supported caliper member supported over the stationary member and capable of moving in the direction of

travel of the sheets and an electric contact device in circuit with the electromagnetic trip mechanism comprising a contact-point, a contact-lever connected with the movable caliper member, and a weighted arm extending from the contact-lever and arranged to hold the parts in normal position, substantially as set forth.

4. The combination, in a paper-feeding machine, with an automatic clutch mechanism constructed to throw the machine out of operation, of a sheet-caliper-clutch-controlling device comprising a lower stationary plate over which the sheets pass, a rigidly-supported slotted plate above the stationary plate, a movable caliper member, a pin or screw passing through the slotted plate and engaging the movable caliper member and supporting it in proper relation to the stationary plate, and means connected with the movable caliper member for tripping the clutch mechanism, substantially as set forth.

5. The combination, in a paper-feeding machine, with an automatic clutch mechanism constructed to throw the machine out of operation, of a sheet-caliper-clutch-controlling device comprising a lower stationary plate over which the sheets pass, a caliper-wheel journaled in a movable support above the stationary plate, means for adjusting the movable support for regulating the distance between the periphery of the wheel and the stationary plate, means of engagement between the wheel and its support to arrest the rotation of the wheel and cause the support to move, and means operatively connecting the movable support with the trip mechanism of the clutch, substantially as set forth.

6. The combination, in a paper-feeding machine, with an automatic clutch mechanism constructed to throw the machine out of operation, of a sheet-caliper-clutch-controlling device comprising a lower stationary plate over which the sheets pass, a vertically-adjustable caliper-plate supported above the stationary plate and arranged to move with the sheets, means connecting the movable caliper-plate to the clutch mechanism, a friction-wheel freely journaled upon the plate with its periphery projecting below the lower face, and a stop device adapted to arrest the rotation of the wheel and cause the caliper-plate to move with the sheets, as set forth.

7. The combination, in a paper-feeding machine, with an automatic clutch mechanism constructed to throw the machine out of operation, of a sheet-caliper-clutch-controlling device comprising a lower stationary plate over which the sheets pass, a vertically-adjustable caliper-plate supported above the stationary plate and arranged to move with the sheets, means connecting the movable caliper-plate to the clutch mechanism, posts or lugs on the caliper-plate, a slot in the plate between the lugs or posts, a friction-wheel journaled between said posts or

5 lugs with its periphery projecting through said slot below the under surface of the plate, and a pin extending from one face of the wheel and adapted to engage one of the posts or lugs, substantially as and for the purpose set forth.

8. The combination, in a paper-feeding machine, with an automatic clutch mechanism constructed to throw the machine out of operation, of a sheet-caliper-clutch-controlling device comprising a lower stationary plate over which the sheets pass, a vertically adjustable caliper-plate supported above the stationary plate and arranged to move 15 with the sheets, means connecting the movable caliper-plate to the clutch mechanism, posts or lugs on the caliper-plate, a slot in the plate between the lugs or posts, a friction-wheel journaled between said posts or lugs with its periphery projecting through said slot below the under surface of the plate, a friction-block of soft rubber inserted in the periphery of the friction-wheel, and a pin extending from one face of the wheel and adapted 25 to engage one of the posts or lugs, substantially as and for the purpose set forth.

9. The combination, in a paper-feeding machine, with an automatic clutch mechanism constructed to throw the machine out of operation, of a sheet-caliper device, a rock-shaft adapted to operate the clutch, a con-

stantly-reciprocating driving-rod operatively connected with the machine and formed with a detent-shoulder, a bar connected with the rock-shaft, a detent pivoted to said bar and 35 adapted to engage the shoulder of the driving-rod, and an electromagnetic trip device under the control of the caliper device, and adapted to hold the detent out of engagement with the driving-rod, substantially as 40 set forth.

10. The combination, in a paper-feeding machine, with an automatic clutch mechanism constructed to throw the machine out of operation, of a sheet-caliper device, a rock- 45 shaft adapted to operate the clutch, a constantly-reciprocating driving-rod operatively connected with the machine and formed with a detent-shoulder, a bar connected with the rock-shaft, a detent pivoted to said bar and 50 adapted to engage the shoulder of the driving-rod, and an electromagnetic trip device under the control of the caliper device and adapted to hold the detent out of engagement with the driving-rod, and a cam-shoulder 55 on the operating-rod adapted to engage the detent and throw it into engagement with the trip mechanism, substantially as set forth.

TALBOT C. DEXTER.
